UNITED STATES PATENT OFFICE.

ENRICO FEROLDI, OF TURIN, ITALY.

CARBURETER FOR EXPLOSION-ENGINES.

1,314,313.

Specification of Letters Patent. Patented Aug. 26, 1919.

Application filed February 28, 1918. Serial No. 219,556.

To all whom it may concern:

Be it known that I, ENRICO FEROLDI, subject of the King of Italy, and resident of Turin, Italy, have invented certain new and useful Improvements in Carbureters for Explosion-Engines, of which the following is a specification.

As it is known in the carbureters for explosion engines the fuel is fed into the constant level or float tank through a needle valve controlled by the float so as to close the fuel inlet orifice when the fuel has reached a given level in said tank.

With such an arrangement when the float 15 is damaged and is filled in with fuel, or the carbureter is reversed, or generally when the float comes out of proper operation, the same float does no longer control the fuel valve and this latter is free to be 20 lifted exceedingly by the fuel pressure so that the fuel tank becomes filled in and the operation of the carbureter is not satisfactory.

This invention has for its object an arrangement 25 allowing of avoiding the drawback objected to by limiting the fuel supply in said float tank to the quantity required for the normal running of the engine even in the cases in which the float 30 does not properly operate to control said needle valve.

The annexed drawing shows by way of example a construction of the carbureter according to this invention, the figure of 35 the drawing being a central section of said construction.

As shown in the drawing, the float tank 1, which may have any required shape and dimensions, is connected with the feeding 40 pipe by means of the connecting piece 2 and communicates with the carbureter nozzle through passage 3; in said tank 1 is arranged the float 4 which controls the needle valve 7 by means of counterweighted 45 levers 5 pivoted at 6 in the cover of tank 1, said needle valve being intended to shut the fuel supplying orifice.

According to this invention the lifting of needle valve 7 is limited by means of a 50 stop to the extent required to allow a proper supply of fuel into the tank, said supply corresponding to the ordinary running of the engine.

This result may be obtained by the construction shown in the drawing, in which 55 the lower end of needle 7 is provided with an enlarged portion 8 which is encircled by a sleeve 9 projecting from the bottom of tank 1 and having holes 10 for the fuel issue. The arrangement and dimensions of 60 portion 8 and sleeve 9 with regard to each other are such as when the needle 7 closes the fuel inlet orifice the upper face of enlarged portion 8 takes place into the sleeve 9 while when said upper face of enlarged 65 portion 8 is at the level of the upper face of sleeve 9, the lifting of needle 7 corresponds to the fuel supply required for the normal running of the engine.

Thus when the float 4 properly operates 70 to control the needle 7, the operation of valve 7 takes place as usual; on the contrary when the float is damaged and filled in with fuel it rests by its weight on the sleeve 9 and thus the needle 7 can be lifted 75 only to the extent required for the proper supply of the engine at its normal running owing to the fact that the enlarged portion 8 comes into engagement with the lower face of said float. 80

The same result is obtained when the carbureter is reversed as in this case the float is carried by its buoyancy against the sleeve 9.

What I claim as my invention and desire 85 to secure by United States Letters Patent is:

In fuel feeding devices for carbureters for explosion engines, a constant level tank in which the fuel is fed, a valve controlling the supply of fuel in said tank, a float operating said valve, means in the tank on which rests the float when it comes out of operation and means on said valve intended to engage said float when it rests on said means to limit the lifting of said valve 90 to the extent corresponding to the fuel supply required for the normal running of the engine. 95

Signed at Turin, Italy, this 15 day of October, A. D. 1917.

ENRICO FEROLDI.
